UNITED STATES PATENT OFFICE.

MARION J. HENRY, OF KANSAS CITY, KANSAS.

GREASE CUP.

Application filed August 6, 1927. Serial No. 211,170.

My invention relates to improvements in grease cups, of the type having an expressing plug provided with threaded connection with the cup, the cup being adapted for use 5 on a locomotive side rod.

One of the objects of my invention is to provide novel means for releasably holding the plug to limit its unscrewing movement due to jarring to which it may be subjected.

A further object of my invention is to provide novel holding means of the kind described, which is simple, cheap, strong, durable, not liable to get out of order, which 15 is easy to manipulate, and efficient in its operation.

The novel features of my invention are hereinafter fully described and claimed.

In the accompanying drawing, which 20 illustrates the preferred embodiment of my invention,

Fig. 1 is a top view of my improved grease cup shown mounted on a portion of a locomotive side rod.

Fig. 2 is a section on the line 2—2 of Fig. 1.

Fig. 3 is a side elevation of the same.

Similar reference characters designate similar parts in the different views.

30 1 designates the body of the grease cup, which is interiorly threaded and has its bottom end fastened, as by welding 2, at its periphery to the top of a locomotive side rod 3, which has a grease conveying hole 4 communicating with a discharge opening 5 in the bottom of the cup 1.

The cup 1 is adapted to contain grease or other lubricating material 6, which is expressed through the opening 5 by a threaded 40 plug 7 fitted in the threaded cup 1. The center and top of the plug 7 may have a square recess 8 adapted to receive a wrench, not shown, with which the plug may be turned.

45 For releasably limiting the turning movement of the plug 7 in the cup 1, so as to prevent the latter from unscrewing, due to jarring action to which it is subjected, I provide a U shaped member 9, one arm 50 of which is fitted and securely fastened in a vertical hole 10 provided eccentrically in the upper end of the plug 7.

The other arm of the U shaped member 9 is disposed beyond the periphery of the

cup 1 around which the said arm is rev- 55 oluble and adapted for movement with the plug 7 lengthwise of the cup.

For engaging the outer arm of the U shaped member 9 to releasably limit the turning movement of the plug 7, I provide 60 on the cup 1 limiting means, which may be one or more springs 11, one end of each of which is fastened securely to the cup, as by a stud 12 of rectangular form, which 65 extends upwardly from the top of the cup 1 through a rectangular opening in the inner end of the spring 11, the upper end of the stud 12 being upset so as to securely hold the spring against the top of the cup.

The outer end of each spring 11 has a V 70 shaped portion 13 which projects beyond the periphery of the cup 1 into the path of the outer arm of the U shaped member 9. This projecting portion 13 of the spring is adapted to engage the said outer arm so 75 as to hold it from revolving in a direction which would permit the plug 7 to unscrew.

Upon turning the plug 7 in either direction the outer arm of the member 9 will strike and force inwardly the outer ends 80 of the springs 11, two of these being shown in the drawing, thus permitting the plug to be manually screwed inwardly or outwardly, but limiting the accidental revolving movement of the plug.

In the operation of the invention, grease 6 is placed in the cup 1, and the plug 7 is then 85 screwed into the cup to a position in which grease will have been forced through the opening 5 and hole 4. In such screwing of the plug 7 the outer arm of the member 9 will press inwardly and pass the springs 11. The V shaped portions 13 of the latter will engage and stop the unscrewing movement 90 of the plug due to the vibration to which it may be subjected, such vibration being insufficient to cause the member 9 to press the springs inwardly so as to allow the outer 95 arm of the member 9 to pass them.

If desired the outer arm of the member 9 100 may be resilient so as to afford a spring action in itself, to enable the operator to unscrew the plug, when it is desired to refill the cup with grease. Such spring action of the outer arm will also relieve the strain upon 105 the springs 11.

I do not limit my invention to the structure shown and described, as modifications,

within the scope of the appended claims, may be made without departing from the spirit of my invention.

What I claim is:

- 5 1. A grease cup having a discharge opening, a rotary plug fitted in and having threaded connection with said cup, a **U** shaped member having one arm fastened to and movable with said plug and having its other arm revoluble around and movable lengthwise of said cup with said plug, and means on said cup adapted to be yieldingly engaged by said other arm for releasably limiting the rotation of said plug.
- 10 15 2. A grease cup having a discharge opening, a rotary plug fitted in and having threaded connection with said cup, a **U** shaped member having one arm fastened to and movable with said plug and having its other arm revoluble around and movable
- 20

lengthwise of said cup with said plug, and a spring on said cup extending beyond the periphery thereof into the path and adapted to releasably limit the revolving movement of said other arm.

25 3. A grease cup having a discharge opening, a rotary plug fitted in and having threaded connection with said cup, a **U** shaped member having one arm fastened to and movable with said plug and having its other arm resilient and revoluble around and movable lengthwise of said cup with said plug, and stop means on and extending beyond the periphery of said cup into the path of said resilient arm for releasably 30 35 limiting the revoluble movement of said other arm.

In testimony whereof I have signed my name to this specification.

MARION J. HENRY.
